UNITED STATES PATENT OFFICE.

FRANK C. HOLBERG, JR., OF PHILADELPHIA, PENNSYLVANIA; ELIZABETH HOLBERG EXECUTRIX OF SAID FRANK C. HOLBERG, JR., DECEASED.

INTERLOCKING DEVICE FOR ELEVATORS.

Application filed August 27, 1923. Serial No. 659,486.

To all whom it may concern:

Be it known that I, FRANK C. HOLBERG, Jr., a citizen of the United States, residing at Philadelphia, county of Philadelphia, 5 and State of Pennsylvania, have invented a new and useful Improvement in Interlocking Devices for Elevators, of which the following is a full, clear, and exact description, reference being had to the accompanying 10 drawings, which form a part of this specification.

My invention relates to an improvement in elevator interlocking mechanism, especially to electric elevators.

15 Heretofore electric elevators have been equipped with automatic control means whereby the elevator car may be started from any floor and stopped automatically at any other floor, selected when the car is 20 started. It is usual to provide the shaft gates and car with interlocking devices, which, when the car is stopped opposite a landing, cooperate to release the gate for opening and prevent the car from being 25 operated when the gate is open.

In connection with electric elevators which are automatically controlled, such as to which my invention is more particularly adaptable, the car and shaft are equipped 30 with shoes which, when the car is level with a landing, cooperate to effect a release of the gate locking mechanism and actuate a switch at the landing adapted to cut off the current from the car when the gate is 35 opened.

The present devices, while satisfactory, are open to a number of objections, particularly in that the car shoe tends to strike the shoes at the landings as the car passes 40 without stopping and in that a switch for cutting off the current from the car is necessary to be provided at each landing and is actuated by the door.

A further disadvantage of the present devices is that it is possible, as the car comes 45 in line with a landing at which it is not intended for it to stop, to open the gate, thus cutting off the current from the car and causing it to stop, which results, if the 50 car be traveling empty, as is frequently the case, in it being possible to "steal" the car in its passage to a landing where it is desired.

In accordance with my invention, I provide 55 an interlocking device wherein, in the

starting of the car, the car shoe is retracted so as to positively clear the gate shoes while the car is in motion, being advanced to operative position when the car is stopped, thus preventing the possibility of the gate being 60 opened as the car passes a landing. Further, by virtue of my invention, a switch for cutting off the current to prevent operation of the car, when the landing gate is 65 open, is positioned on the car and is actuated, through actuation of the car shoe on opening of a gate at any landing, to prevent operation of the car after stopping at a landing.

Thus, by virtue of my invention, striking 70 of the car and landing shoes, while the car is in motion, is eliminated and not only is the necessity for a cut-off switch at each floor avoided, but the cut-off switch can only be operated when the car is at rest opposite 75 a landing, thus preventing the possibility of stealing the car.

Having now indicated in a general way the nature, purpose and advantage of my invention, I will proceed to a detailed description of a preferred embodiment thereof 80 with reference to the accompanying drawings, in which:—

Fig. 1 is a partial face view of an elevator shaft landing gate and of that portion 85 of the interlocking mechanism coacting therewith.

Fig. 2 is a cross-sectional view showing the coacting members of the interlocking mechanism.

Fig. 3 is a plan view, partly in section, showing the coacting parts of the interlocking mechanism and means for withdrawing the car shoe.

Fig. 4 is a plan view showing the shoe 95 withdrawing means and cut-off switch and connections, the parts being in the position occupied when the car is in motion.

Fig. 5 is a view showing the subject of Fig. 4 with the parts in the position they 100 occupy when the car is stopped opposite a landing.

Fig. 6 is a view showing the subject of Fig. 4 with the parts in the position they 105 occupy when the landing gate is opened.

Inside the elevator shaft at each landing x is secured a plate a , which carries the locking mechanism for the landing gate y . z represents the floor of an elevator car, shown as on a level with a landing.

A bar *b* extends downward from the gate over the face of plate *a*, the end of the bar being adapted to engage in a notch in a locking disc *c*, when the gate is closed or 5 only slightly open.

The position of bar *b* and disc *c*, when the gate is fully closed, is shown in Fig. 1.

A lug *d* is positioned on disc *c* and the disc *c* is pressed outwardly from behind by a 10 spring, not shown. The lug *d* is adapted, if it be attempted to open the gate when the car is not at a landing, to contact with the end of an angle piece *e*, secured to plate *a*, and stop the disc *c* before the bar *b* can be 15 withdrawn from the disc, thus preventing the gate from being opened.

Disc *c* carries a cam surface *f* adapted to underride the free end of a plate *h*, hinged on a vertical pivot to plate *a*. A ridge *i*, 20 forming a shoe, is formed on the front of plate *h* adjacent its free end.

If now the plate *h* be prevented from swinging on its pivot until lug *d* has passed the end of angle piece *e* and it be attempted 25 to open the door, plate *h* will, as disc *c* turns, press the disc back against the action of its spring and permit lug *d* to pass behind angle piece *e* and continue to turn until another lug *d'*, on plate *a*, contacts with a stop *g* 30 on plate *a*, by which time disc *c* will have been turned to a position at which rod *b* may freely slide out of its slot and the gate is free to open. In the movement of disc *c* due to the action of cam *f*, the free end of 35 plate *h* is swung outwardly after lug *d* has cleared the end of angle plate *e*.

In order to prevent plate *h* from swinging until lug *d* has cleared the end of piece *e*, 40 permitting the gate to be opened when the car is level with the landing, and in order to prevent operation of the car when the gate is open, certain mechanism is carried by the car.

Beneath the car and extending parallel 45 to the edge of the landing floor is secured the angle frame *j* through which extends a sleeve *k*. Within the sleeve and connected to it by a slot and pin connection *v* is a plunger *l* pressed outwardly by a spring *w* 50 and having pinned to its forward end a shoe *m*.

To the sleeve is pivotally connected one 55 end of a link *n*, the other end of which is pivotally connected to an end of a second link *o*, the other end of which is connected to a crank *r* and the movable member of a switch *s*, and to a link *p* which is connected to a solenoid *q*. The links *n* and *o* form a toggle. A spring *t* is connected with crank 60 *r* and tends to hold it against stop *u*.

The switch *s* is connected with the line 65 supplying power to actuate the car and is so arranged that if it be closed, power will be cut off from the car and it cannot be actuated. The solenoid is connected with

the control of the car in such a manner that when the car is in motion current will be on the solenoid, and when the car is stopped the solenoid will be cut out.

The operation of the device will now, it is 70 believed, be apparent from observation of Figs. 4, 5 and 6. Assuming that the car is in motion, current will enter the solenoid *q* and the toggle will be pulled to retract shoe *m*, as shown in Fig. 4. If the car is 75 stopped opposite a landing, the shoe *m* will lie opposite ridge *i* on plate *h*, and on the stopping of the car current will be cut off from the solenoid *q* and the toggle will straighten out advancing shoe *m* close to 80 the ridge *i* on plate *h*. On the opening of the gate, plate *h* will be swung outwardly by cam surface *f* and shoe *m* will be pushed back, the movement being transmitted through the straightened toggle to open 85 switch *s*, to cut off the current and prevent operation of the car, as shown in Fig. 6.

So long as the gate is open the parts will remain as shown in Fig. 6 and the car 90 cannot be operated, but on closing the gate, the end of plate *h* is released from cam surface *f* and shoe *m* will be advanced by the spring *t*, acting on crank *r*, sufficiently to effect a closing of switch *s*. With switch *s* closed, the car may be operated and upon 95 its being started current will enter solenoid *q* and effect the retraction of shoe *m*, as described.

Having now fully described my invention, what I claim and desire to protect by Letters Patent is:

1. In an interlocking device for automatically controlled electric elevators in combination with a shaft, provided with a landing and a gate therefor, and an elevator car, a shoe at the landing adapted to be advanced on the opening of the door, a shoe on the car adapted to align with the landing shoe, when the car is on a level with the landing, and be retracted by the landing shoe when 105 the gate is opened, a cut-off switch on the car, means affording a connection between the car shoe and the said switch whereby, when said shoe is retracted on the opening of the gate, said switch will be operated to 110 cut off current from the car, and means adapted to effect retraction of said car shoe without actuating said cut-off switch when the car is operated.

2. In an interlocking device for automatically controlled electric elevators in combination with a shaft, provided with a landing and a gate therefor, and an elevator car, a shoe at the landing adapted to be advanced on the opening of the door, a shoe on the car adapted to align with the landing shoe, when the car is on a level with the landing, and be retracted by the landing shoe when 115 the gate is opened, a cut-off switch on the car, means affording a connection between 120 the car shoe and the said switch whereby, when said shoe is retracted on the opening of the gate, said switch will be operated to cut off current from the car, and means adapted to effect retraction of said car shoe without actuating said cut-off switch when the car is operated.

125

130

said car shoe and said cut-off switch whereby said cut-off switch will be actuated to cut off current from the car when the gate is opened, means to advance said shoe and 5 actuate said switch to permit operation of the car when the gate is closed, and means actuated electrically, when the car is operated, to retract the car shoe without actuating said cut-off switch.

10 3. In an interlocking device for automatically controlled electric elevators in combination with a shaft, provided with a landing and a gate therefor, and an elevator car, a shoe at the landing adapted to be advanced 15 on the opening of the door, a shoe on the car adapted to align with the landing shoe, when the car is on a level with the landing, and be retracted by the landing shoe when the gate is opened, a cut-off switch on the 20 car, a solenoid, and a toggle affording connection between said car shoe, said cut-off switch and said solenoid, said solenoid being so connected as to receive current when the car is operated and effect a retraction of said 25 car shoe and to be cut off when the car is stopped, permitting the car shoe to advance to a position for retraction by said landing shoe, on opening of the gate, to actuate said cut-off switch to cut off current 30 from the car.

4. In an interlocking device for automatically controlled electric elevators in combi-

nation with a shaft, provided with a landing and a gate therefor, and an elevator car, a shoe at the landing adapted to be advanced 35 on the opening of the door, a shoe on the car adapted to align with the landing shoe, when the car is on a level with the landing, and be retracted by the landing shoe when the gate is opened, a cut-off switch on the 40 car, a pair of pivotally connected rods affording a connection between said car shoe and said cut-off switch, a spring tending to maintain said cut-off switch in an inoperative position and said car shoe advanced in 45 a position for retraction by said landing shoe, a solenoid positioned above said rods, and a link pivotally connected to the movable element of said solenoid and to the pivotal connection of said rods, said solenoid 50 being connected in circuit to receive current when the car is operated and effect a retraction of said car shoe without actuating said cut-off switch, and to be cut off when said car is stopped, to permit said spring to advance 55 said car shoe and said landing shoe to retract said car shoe, when the gate is opened, to effect actuation of said cut-off switch to cut off current from the car.

In testimony of which invention, I have 60 hereunto set my hand, at Philadelphia, Pa., on this 4th day of March, 1923.

FRANK C. HOLBERG, JR.
